UNITED STATES PATENT OFFICE.

JOHN DEMAN, OF DETROIT, MICHIGAN.

BRUSH-SUPPORTING DEVICE.

Application filed January 12, 1925. Serial No. 2,015.

To all whom it may concern:

Be it known that I, JOHN DEMAN, a citizen of the United States, and residing at Detroit, in the county of Wayne and State 5 of Michigan, have invented a new and Improved Brush-Supporting Device, of which the following is a specification.

This invention relates to brush supporting devices and is adapted for use on paint pails 10 or paste pails used by painters and paper hangers.

One of the principal objects of the invention is to provide a device for supporting a brush when not in use above the paint or 15 paste in the pail in order to keep the brush clean.

Another object of the invention is to provide a device of the character described which is adjustable to fit different sized pails 20 and which may be folded to be carried in the pocket when not in use.

A further object of the invention is to provide a brush support which may be made entirely of sheet metal and is therefore of very 25 low manufacturing cost.

These objects and the several novel features of the invention are hereinafter more fully described and claimed and the preferred form of construction by which these 30 objects are attained is shown in the accompanying drawings in which—

Fig. 1 is a plan view of the device as applied to a pail.

Fig. 2 is a section taken on line 2—2 of 35 Fig. 1.

Fig. 3 is an enlarged elevation of the device in the folded position.

Fig. 4 is an enlarged section taken on line 4—4 of Fig. 3.

The device as shown in Fig. 3 comprises 40 three arms 1, 2 and 3 and the arm 1 as shown in Fig. 4 is provided with a tubular extension 4 extending through apertures provided therefore in the arms 2 and 3. This tubular 45 extension 4 pivots the arms 1, 2 and 3 together and is provided with an outwardly extending flange 5 to prevent removal of the arms 2 and 3 therefrom. Each arm 1, 2 and 3 is provided with an extension comprising a member 6 provided with inturned lugs 7 upon the respective arm so that the member 6 is slidable thereon. Each member 6 is provided with two depending ends 8 and 9 adapted to fit against the inner edge 55 of the pail and each member 6 is also provided with a depending end 10 spaced from

the ends 8 and 9 and adapted to engage over the outer edge of the pail as shown in Fig. 2, and the portion 10 is turned outwardly at the lower end to more easily engage over the 60 edge of the pail.

In operation the end of one member 6 may be engaged over the edge of the pail at which time the other arms may be turned on the pivot to the desired position and the 65 ends of these arms may be also engaged over the edge of the pail. The device is then ready for use and the brush may be positioned thereon as shown in dotted lines in Fig. 1, instead of being dropped into the 70 pail as is the usual custom. By the use of this device the brush is not placed in the pail when not in use and thus the brush is kept in a clean condition. By means of the 75 movable member 6 the device may be adjusted for use on pails of different sizes and does not interfere with movement of the bail of the pail. The device may be easily removed from the pail and the different 80 arms may be turned on the common pivot to the position shown in Fig. 3 to provide a compact package which may be easily carried in the pocket.

From the foregoing description it becomes evident that the device is very simple 85 and efficient in operation, will not easily get out of order, is composed of few parts and is of consequent low manufacturing cost, and provides a device which accomplishes the 90 objects described.

Having thus fully described my invention, its utility and mode of operation, what I claim and desire to secure by Letters Patent of the United States is—

1. A brush support for a pail comprising 95 an arm having a tubular extension at one end, a pair of arms rotatable on the tubular extension, the tubular extension being flanged outwardly to secure the arms thereon and a slidable extension on each arm having spaced depending ends between which the edge of the pail is adapted to be engaged.

2. A paint or paste brush support for 100 paint or paste pails comprising a series of three arms pivoted together, an extension slidable on each arm and having spaced depending ends, the edge of the paint or paste pail being adapted to be engaged between the spaced depending ends.

3. A brush support for a paint or paste 110 pail comprising an arm having a tubular extension at one end thereof, a pair of arms

rotatable on the tubular extension, the tubular extension being flanged outwardly to prevent removal of the rotatable arms, and a slidable extension mounted on each arm and provided with means for engaging over the edge of a pail.

4. A brush support for attachment to a

receptacle comprising a series of three arms pivoted together and an extension slidable on each arm and provided with means for 10 engaging the edge of the receptacle.

In testimony whereof I sign this specification.

JOHN DEMAN.
